UNITED STATES PATENT OFFICE.

AUSTIN FREDERICK JACKSON, OF TAUNTON, MASSACHUSETTS, ASSIGNOR
TO REED & BARTON, OF SAME PLACE.

DESIGN FOR A HANDLE FOR KNIVES, FORKS, SPOONS, &c.

SPECIFICATION forming part of Design No. 17,007, dated November 30, 1886.

Application filed October 30, 1886. Serial No. 217,635. Term of patent 7 years.

To all whom it may concern:

Be it known that I, AUSTIN FREDERICK JACKSON, of Taunton, in the county of Bristol and State of Massachusetts, have invented and produced a new and original Design for Handles for Knives, Forks, Spoons, &c., of which the following is a specification, reference being had to the accompanying photographic illustration, forming part thereof, 10 which represents a side view of the design.

The design for the handle is raised or struck up in bold relief, both sides being alike and presenting the following configuration. At the butt-end of the handle there is a mask or 15 face, *a*, surrounded by a fanciful head-gear, *a'*. At the neck of this figure there hangs an oval panel, *b*, bearing a fruit piece, *b'*, surrounded by scrolls and flowers *b''*. Between this panel and the blade, and extending about half the 20 length of the handle, there is a long panel, *c*, having a background of parallel transverse

lines, and bearing on its face, in the middle, an elongated spray of flowers, *c'*, and having a band, *c''*, on each side divided into aliquot spaces and flanked on each side by overlapping tuberoses *c'''*. Where the handle joins the blade there is a band, *d*, of plainer design, composed of crossed lines having at their intersections quarterfoil figures. 25

What I claim is—

In a design for a knife, fork, spoon, &c., the handle having the face *a*, with head-gear *a'*, panel *b*, with fruit piece *b'* and a border of flowers and scrolls, panel *c*, bearing spray *c'*, bands *c''*, and overlapping tuberoses *c'''*, and 30 transverse band *d*, provided with cross-lines with quarterfoil figures at their intersection. 35
